(57) **CLAIM**

The ornamental design for a bucket bag, as shown and described.

DESCRIPTION

FIG. 1 is a perspective view of a bucket bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the bucket bag where the bucket bag is in a configuration of use.

The short thick evenly spaced broken lines in the drawings depict stitching and form no part of the claimed design. The long thin evenly spaced broken lines in the drawings depict portions of the bucket bag that form no part of the claimed design.

1 Claim, 9 Drawing Sheets
